UNITED STATES PATENT OFFICE

2,486,339

RAILWAY CAR DOOR FIXTURE

Stanley J. Stone, Munster, Ind., assignor to
Standard Railway Equipment Manufacturing
Company, Chicago, Ill., a corporation of Dela-
ware

Application November 25, 1946, Serial No. 712,184

5 Claims. (Cl. 16—96)

1

The invention relates to a slidable side door for a railway house car and particularly to such a door supported by rollers adjacent the lower margin thereof which roll upon a track fixed to a car, which track is provided with spaced depressions or interrupted portions into which the rollers fall when the door is in a predetermined position (such as fully open or fully closed position) so that the door will engage the track and relieve the rollers of the weight of the door. Such a structure is shown in Gilpin Patent No. 1,902,772 of March 21, 1933, and my fixture is an improvement thereon.

The principal object of the invention is to provide a door track having parallel treads to engage certain rollers, respectively which are mounted upon the door in spaced planes parallel with the car door, said treads having interrupted portions therein adapted to receive said rollers and thereby allow the door to lower and rest upon the track when in closed or open position, and to associate and arrange the interrupted portions relative to the rollers so that each roller rolls upon a smooth tread when the door is moved from open to closed position or vice versa.

A further object of the invention is to provide a roller housing wherein a roller may be mounted in either of two (or more) planes parallel to the door, and to provide roller housings which are interchangeable with each other and which may be attached to the bottom margin of the door at the corners thereof, or at any point along said margin as may be required for different widths of doors, and so that the rollers may be suitably spaced to suit the spacing of the tread depressions.

In the drawings:

Figure 1 is a side elevation of the lower portion of a railway car door and adjacent car sides showing the invention.

Figure 2 is a top plan view of the track showing the preferred arrangement of the interrupted portion of the treads.

Figure 3 is an enlarged section through the roller housing and associated parts of the car showing the roller positioned near the door to engage the inner tread of the track.

Figure 4 is a view similar to Figure 3, showing the roller positioned remote from the door to engage the outer tread of the track.

Figure 5 is a plan view of a modified track.

Figure 6 is a side view of Figure 5.

Figure 7 is a plan view illustrating one manner of maintaining a smooth tread opposite an interrupted portion of an adjacent tread.

2

Figure 8 is a side elevation of Figure 7.

In the drawings, the car door is illustrated at 1, the door threshold plate at 2, the side sill at 4, flooring at 5 and side wall at 6.

- 5 The rollers 8 and 9 are mounted in housing 10 upon the door in spaced planes parallel to the door, as shown clearly in Figures 3 and 4, wherein the roller 8 is positioned near the door, as in Figure 3, and the roller 9 is positioned, relatively speaking, remote from the door, as in Figure 4. Any roller may be changed from one position to the other position by removing the pin 11 and interchanging the roller and filler 12, thus the same housing 10 may be used for a roller in either position. This is desirable so that the same housing may be used near the front of the door as is used near the rear of the door. The housings 10 are secured to the door, as by the rivets 13.
- 10 20 The door track 14 has spaced treads 15 and 16 (even though shown in Figure 2 as a single unit). The near roller 8 rolls upon one of said treads 15 and the remote roller 9 rolls upon the other of said treads 16. The portions of the treads upon which the rollers roll are smooth but the treads are provided with interrupted portions 17, 18, 19 and 20 into which the rollers roll and thereby allow the door 1 to move downwardly and rest upon the track 14 when the rollers move into said interrupted portions. The interrupted portions of the treads are arranged and positioned so that the door will rest upon the track when the door is in fully closed position, as shown in Figure 1, or fully open position.
- 15 25 30 35

- 30 35 In order for the door to run smoothly from open to closed position, or vice versa, I provide an uninterrupted tread 15 for the front roller 8 and another uninterrupted tread 16 for the back roller 9. This is accomplished by having certain portions of the upper surface of the track with one tread smooth and the adjacent tread interrupted. This may be done by depressing the entire track and then filling in one tread with a filler 22, as shown in Figures 7 and 8, preferably held in place by welding material 21.

- In Figures 5 and 6 there is shown a modified track wherein a pair of members 25 and 26 are arranged so that their ends overlap and are secured together by the rivets 27, or other securing means. Thus the members 25 and 26 form treads 28 and 29 in spaced planes upon which the rollers 8 and 9, mounted in coincident spaced planes, may roll. In this modification instead of providing depressions in the track to provide the interrupted portions, the treads are terminated so

that the rollers roll off the ends of said treads, (see Figure 5) and thereby allow the door to lower and rest upon said track. The ends of the treads in this modification are turned downwardly, as at 30, to facilitate rolling of the rollers on and off of said treads.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. For use in a railway car having a horizontally slidable door, the combination of spaced rollers adapted to be secured to said door in spaced planes parallel to the door, and a track having treads in spaced planes parallel to the door, one of said rollers adapted to roll upon one of said treads and the other of said rollers adapted to roll upon the other of said treads, each tread having longitudinally spaced depressions, one for receiving its respective roller in the open position of the door, and the other for receiving said roller in the closed position of said door.

2. For use in a railway car having a horizontally slidable door, the combination of spaced rollers adapted to be secured to said door in spaced planes parallel to the door, and a track having treads in spaced planes parallel to the door, one of said rollers adapted to roll upon one of said treads and the other of said rollers adapted to roll upon the other of said treads, each of said treads having longitudinally spaced depressions to relieve the respective rollers of the weight of the door when the door is in predetermined position.

3. For use in a railway car having a horizontally slidable door, the combination of spaced rollers adapted to be secured to said door in spaced planes parallel to the door, and a track having treads, said treads overlapping each other in spaced planes parallel to the door, one of said rollers adapted to roll upon one of said treads and the other of said rollers adapted to roll upon the other of said treads, each of said treads being shorter than the distance each roller travels from open to closed position of the door so as to run

off the end of said tread and thereby relieve the rollers of the weight of the door when the door is in predetermined position.

4. For use in a railway car having a horizontally slidable door, the combination of spaced rollers adapted to be secured to said door in spaced planes parallel to the door and between the vertical margins of the door, and a track having overlapping treads in spaced planes parallel to the door, one of said rollers adapted to roll upon one of said treads and the other of said rollers adapted to roll upon the other of said treads, each tread being shorter than the distance its respective roller travels from the open to the closed position of the door.

5. In a railway car having a wall, a doorway in said wall, a sliding door for closing said doorway, and a pair of interchangeable roller housings secured in spaced relation upon the lower margin of said door; a roller mounted in each housing, said rollers being mounted so as to occur in spaced planes parallel to the door, a track mounted upon said car below said door, said track having treads in spaced planes coincident with the planes of said rollers, so that one roller is adapted to roll upon one of said treads and the other roller is adapted to roll upon the other of said treads, each tread having longitudinally spaced interruptions therein, the interruptions in each tread being spaced apart a distance greater than the distance between the respective rollers and so that when the door is moved from closed to opened position each roller will have moved from one interruption to the other.

STANLEY J. STONE.
